UNITED STATES PATENT OFFICE.

THOMAS J. GRAFF, OF PITTSBURG, PENNSYLVANIA.

POR TABLE STOVE OR RANGE.

SPECIFICATION forming part of Letters Patent No. 395,131, dated December 25, 1888.

Application filed May 25, 1888. Serial No. 275,045. (No model.)

To all whom it may concern:

Be it known that I, THOMAS J. GRAFF, a resident of Pittsburgh, in the county of Allegheny and State of Pennsylvania, have invented a new and useful Improvement in Portable Stoves or Ranges; and I do hereby declare the following to be a full, clear, and exact description thereof.

My invention relates to portable ranges or stoves which are constructed so as to be used as right or left hand, as desired, according to the position of the fire-place and sink in the room. In this class of ranges it has been customary to have them so constructed that the flue-box is cast separate from the body of the range or stove and adapted to be attached thereto by suitable means to either side of the range said flue-box either having a pipe-collar formed therewith or else the part of the top plate having the pipe-collar being reversible, and when it is desired to reverse the range the flue-box is removed and secured to the opposite side and the top plate reversed, so that the pipe-collar will be above the flue-box, while a flat plate covers the recess formerly covered by the flue-box. Where so many parts have to be removed to reverse the range much inconvenience is experienced, as the bolts or screws by which the parts are attached become burned and broken, owing to the intense heat to which they are exposed.

The object of my invention is to provide a simple and efficient means of changing the range or stove from right to left hand, or vice versa, without the use of a detachable flue-box or other such reversible parts, and, furthermore, to provide means for adjusting the pipe within openings either in the top of the range or in the side, as is desired, to carry off the products of combustion.

To these ends my invention consists in a range or stove both side plates of which are formed with enlargements or flue-boxes which extend toward the rear of the range, and openings leading from said flue-boxes through top plate to carry off the smoke, and plates for covering said openings when not in use, such plates forming extra lids for the range, in combination with the central division-plate in the top flue and a deflecting-plate in front of the smoke-flue in use.

To enable others skilled in the art to make

and use my invention, I will describe the same more fully, referring to the accompanying drawings, in which—

Figure 1 is a top view. Fig. 2 is a like view, the top plates removed. Fig. 3 is a section on the line $x-x$, Fig. 2; and Fig. 4 is a detail view showing another way of arranging the smoke-escape.

Like letters of reference indicate like parts in each.

The grate, ash-pit, ovens, &c., are those used in any ordinary range or stove, and therefore need no further description. The side plates, a , are cast with the enlargement a' at the top thereof, so that when the range is set enlargements or flue-boxes b are formed within the range on each side of the top flue thereof, and I prefer to have the said enlargements or flue-boxes b extending entirely to the rear end of the range.

The top of the range is provided with covering-plates c and lids c' , fitting therein, and openings d in said top plates, c , lead from the enlargements or flue-boxes b , through which the products of combustion are carried off, while openings may also be formed in the side plates, a , communicating with said flue-boxes, as at e , if it is desired to carry off the smoke in that way. As only one flue-opening, d , in the top plate, c , is used at a time, the other such opening is closed by suitable lid or cover, d' , and said lid d' on the top surface of the range fits in a seat, d^2 , and rests on suitable lugs or a flange cast on the surface-plate of the range in the same manner in which the lids c' rest in the top plate, c , said lid d' being also supplied with the usual seat, d^2 , to which the ordinary lid-lifter may be applied to raise it. By this construction the opening d , supplied with the covering-plate d' , can be used as extra lid and perform the same function as the lids c' . The side covering-plates, e' , are attached to the side plates, a , and cover the openings e by means of bolts passing through the cover-plates and through lugs e^2 , cast on the side plates, a , of the range within the openings e , by which they are held securely in place.

To adjust the stove-pipe f , which is supplied with a suitable flange or collar, f' , near its lower end, is inserted into the opening d , said flange or collar f' resting on the

flange or lip d^2 , and thereby supporting the stove-pipe. Instead of the above manner of attaching the stove-pipe, the pipe-collar g (shown in Fig. 4) may be employed, said pipe-collar having suitable lugs, g' , cast thereon and adapted to coincide with corresponding lugs, g^2 , cast in the openings d or e in the top or side plates of the range, both of said lugs being supplied with bolt-holes, through which 10 pass the bolts g^3 , supplied with suitable nuts. The pipe is then adjusted around the pipe-collar in the ordinary way.

The range or stove is supplied with the customary top, end, and bottom flues, the end 15 one, h , and the bottom one (not shown in the drawings) being divided into two compartments by central longitudinal partitions. The top flue, i , has the partition-wall i' in the center thereof and in a line with the partition-wall 20 h' of the flue h , while the middle portion of said partition-wall i' is constructed to form the hinged damper l , adapted to be raised or lowered from a point without. Attached to the damper l are the rings k , which form bearings 25 for a rod, k' , said rod being journaled in the end portions of the partition-walls i' . To raise and lower the damper l , a rod, m , with a ring, m' , on one end thereof and attached to the top of the damper, passes through an opening, m^2 , in the side plate, a , of the range to a 30 point without, where by a suitable handle, m^3 , the damper is operated. The rod m is attached in such a manner to the damper l that when it is desired to operate it from the 35 opposite side from that shown in the drawings all that is necessary is to detach the rod from the damper and pass it through a like opening, m^2 , in the opposite side plate, and then reattach it to the damper.

40 Pivoted at the forward end of the central division-plate, i , by a suitable pintle, n' , is the deflecting-plate n , while the other end of said deflecting-plate is secured to a lug, n^2 , cast on the body of the range, a bolt or pin passing 45 through the deflecting-plate and lug n^2 , and a like lug, n^3 , being formed on the opposite side, so that the flue-plate n can be swung on its pintle from one side to the other, according to the flue-box employed, and secured in place.

50 When it is desired to change the range or stove from a right to left hand, or vice versa, all that is necessary is to remove the covering-plate d' and adjust within the opening d the stove-pipe with the collar or flange f' thereon, by which the pipe is supported, while the covering-plate d' covers the opening which had been occupied by the pipe and serves the purpose of an extra lid. No screws or bolts are necessary in this operation, and it conse-

55 quently requires little labor or time. If, however, the ordinary pipe-collar is used, as shown in Fig. 4, the collar g is detached by removing the bolts which pass through the lugs g' and g^2 , and said pipe-collar is attached in the same way to the opposite top side opening of the 60 flue-box.

When the left-hand flue-box is in use, the deflecting-plate n is secured in the position shown in Fig. 2 and directs the products of combustion away from the flue-box in use into 65 the compartment on the right, and if it is desired to heat the ovens the damper l will be in its upright position, so that the products of combustion can pass down the right side of the rear flue and along the same side of the 70 bottom flue and end flue up and out the stove-pipe, and by this indirect route the ovens become thoroughly heated. When a direct draft is desired, the damper l is lowered by the handle m^3 of the rod m , and the products of combustion pass directly to the flue-box and out the stove-pipe. When the opposite flue is to be employed, the deflecting-plate n is detached from the lug n^2 , to which it was secured by 75 the bolt or pin n^3 , and is swung over and attached in the same manner as before to a corresponding lug on the opposite side of the range, while the rod m , attached to the damper l , is changed to the corresponding opening on 80 the opposite side.

I am thus enabled to obtain a right and left hand stove which can be used in either position without the necessity of taking it apart or reversing any of the castings permanently 85 attached, and can therefore be arranged for use in either position with but little time or trouble.

What I claim as my invention, and desire to 90 secure by Letters Patent, is—

A portable range or stove having enlargements a on each side of its top flue, forming smoke-flues b , openings in the top plate above said flues b , said openings forming smoke-escapes, with one of which the smoke-pipe connects, while the other is closed by a cover and forms an extra lid for the stove, a central division-plate in the smoke-flue, and a deflecting-plate therein in front of the smoke-flue in use, substantially as and for the purposes set 95 forth.

In testimony whereof I, the said THOMAS J. GRAFF, have hereunto set my hand.

THOMAS J. GRAFF.
